UNITED STATES PATENT OFFICE.

JOHN T. H. DEMPSTER, OF SCHENECTADY, NEW YORK, ASSIGNOR TO GENERAL ELECTRIC COMPANY, A CORPORATION OF NEW YORK.

STARTING MEANS FOR VAPOR ELECTRIC APPARATUS.

1,093,545.

Specification of Letters Patent. Patented Apr. 14, 1914.

Application filed December 19, 1903. Serial No. 185,771.

To all whom it may concern:

Be it known that I, JOHN T. H. DEMPSTER, a citizen of the United States, residing at Schenectady, in the county of Schenectady and State of New York, have invented certain new and useful Improvements in Starting Means for Vapor Electric Apparatus, of which the following is a specification.

My present invention relates to vapor electric devices such as lamps, rectifiers or the like, and comprises means whereby apparatus of this character may be conveniently started into operation.

The points of novelty of the various features of construction of my invention, both in their broad and limited aspects, I have set forth with particularity in the appended claims.

For a more complete understanding of my invention, both of the details of construction of the same and mode of operation, reference is to be had to the following description taken in connection with the accompanying drawings, in which—

Figure 1 represents a mercury vapor lamp embodying my invention; Figs. 2 and 3 are sectional views on a somewhat enlarged scale of a detail forming part of Fig. 1; Fig. 4 is a modified embodiment of my invention; Fig. 5 is a modified detail forming part of the device shown in Fig. 4; Fig. 6 is a modification in which a single magnetizing coil is used; and Fig. 7 is a modification in which current may be conveyed to the filament and the anode through the same leading-in conductor.

In the drawings I show my invention embodied in a mercury vapor lamp but it is to be understood that the invention is equally applicable for starting other vapor electric devices.

In Fig. 1, the exhausted envelop of the lamp consists of a straight tube 1 which forms the light-giving element of the lamp, the enlargement or bulb 2 at the top of the tube forming a condensing chamber for the mercury vapor generated during normal operation. The lamp is provided with two electrodes, one consisting of a body of mercury 3 in the lower end of the tube, to which electrical connection is made by the leading-in conductor 4, and the other of a cylindrical body 5 of carbon, graphite or other suitable material suspended from the top of the lamp by the wire 6 the upper end of

which passes through the wall of the bulb 2 and serves to transmit current through the wall of the envelop. This wire 6 is surrounded loosely by a glass tube 7 the upper end of which is fused to the wall of the bulb 2 and the lower end of which flares over and into close proximity to the upper end of electrode 5. From this electrode 5 a filament 8 of carbon extends through guides or anchoring devices 9, 10 and 11 into contact with electrode 3 as indicated. The guides 9, 10 and 11 are provided with bushings 12, 13 and 14 of carbon or similar infusible material so that the filament if accidentally heated intensely will not stick to the guide or anchoring device, as would be the case were the latter formed merely of glass. In order to start the lamp the filament 8 is lifted—that is, bodily displaced lengthwise with respect to the envelop—so as to break connection with the electrode 3. The means whereby this lifting or motion of translation is accomplished will be made apparent by reference to Figs. 2 and 3. These figures, which are views in section of electrode 5, show the latter to be constructed in two parts 15 and 16 arranged to be screwed together. The lower half 16 of the electrode is provided with an axial bore permitting the free movement therein of an iron or steel tube 17 the upper end of which is split and provided with a nut 18 fitting tightly thereon so that when screwed into position it urges together the split portion of the tube. The filament 8 projects up through the tube 17 and is pinched against the tube when the nut 18 is screwed into place. This nut, when the parts are in position, rests upon the upper end 19 of the lower member 16 of the electrode. The upper member 15 of the electrode is hollowed out as at 20 so as to permit the nut 18, together with the parts carried thereby, to be raised from its seat on the part 19 and thereby be permitted a limited vertical movement. In order to apply a lifting force to the tube 17 and its connected parts I surround the electrode 5, when the latter is in place, with a solenoid or magnetizing coil 21 located above the center of symmetry of the tube 17 and the head or nut 18. When this coil is energized by the passage of current therein, the tube 17 and the nut 18, being of magnetic material, together form an armature or core for the solenoid.

Under the influence of the magnetic force exerted by the solenoid, the armature is lifted out of its seat and thus raises the filament out of engagement with the mercury 5 3 in the lower end of the tube 1. The solenoid 21 may be connected in series with the electrodes of the lamp as shown or supplied with current from a separate circuit as desired. In either case however as soon as 10 the filament 8 is lifted out of engagement with the mercury electrode 3 an incipient arc is formed which arc extends instantly along the filament 8 from the electrode 3 to the electrode 5 thus putting the lamp 15 into operation.

The lamp shown in Fig. 4 differs from that shown in Fig. 1 mainly in that the starting filament 22 is suspended, not from the carbon or graphite electrode 23, but from 20 a separate support 24 consisting of a rod or wire sealed through the upper end of a small tubular projection 25 extending from the upper wall of the condensing chamber 26. A shell 27 of magnetic material is adapted 25 to slide up and down on the rod 24 and in its lower position is supported by the upset end 28 of this rod. A split screw-threaded plug 29 with axial grooves formed therein is adapted when screwed gently into place to 30 clamp the upper end of the filament 22 into fixed relation with the tubular armature 27. The electrode 23, to which reference has 35 been made, is supported from the upper end of the condensing chamber 26 by means of a wire or rod 30 sealed through the wall of the condensing chamber and passing down through a tubular glass casing 31 to the electrode around which it is passed to hold the latter in place. In order to 40 elevate the filament 22 and thus start the lamp, a solenoid or magnetizing coil 32 surrounds the upper portion of the tubular armature 27 and, when energized upon connection of the lamp in circuit, raises the armature and 45 its depending filament and thus causes by reason of the arc produced at the lower end of the filament, an immediate starting of the lamp. By reason of the high resistance interposed by that portion of the filament 50 between the electrode 23 and the armature by which the filament is carried, the arc when started extends up the tube only to the electrode 23 and not beyond. Current therefore practically ceases to flow in the filament, and consequently in the magnetizing coil 31 in series therewith; whereupon the filament tends to drop back to its original 55 position. To prevent this from happening I provide an additional magnetizing coil 33 60 connected in series with the electrode 23. It will thus be seen that when current ceases to flow in coil 32 it commences to flow in the coil 33. The filament 22 is therefore at all times, when the lamp is in operation, 65 held out of engagement with the mercury

electrode 34. It will be noted, as indicated by the dotted lines on the electrode 23, that the latter is hollow, and that the filament 22 extends down through the electrode without touching the sides thereof. If desired however an arrangement may be used such as shown in Fig. 5, in which the filament, in this case indicated at 35, extends down through a carbon-bushed guide 36 formed integrally with the glass tube 37 which surrounds the conductor 38 leading to the electrode 39, which in this case is solid or hollow as desired. The filament 35 thus passes along one side of the electrode but not through it as in Fig. 4. To provide against excessive heating and consequent disintegration of the lower end of the filament of the lamp where it engages the mercury electrode, the end may be enlarged as shown at 40. This enlargement may be integral 75 with the filament and formed out of the same material as the filament, or it may be a separate piece of titanium carbide, graphite or the like cemented or otherwise secured to the end of the filament.

The lamp which I have above described may be mounted in a variety of ways. One way which I have found convenient is to support the lamp from a conical or other reflector such, for example, as indicated at 41 in Fig. 1 and in a slightly different form at 42 in Fig. 4. In Fig. 1 the magnetizing coil 21 is carried by inwardly extending radial fingers as 43 integral with the reflector. The spaces between these fingers form ventilating openings, such as 44, allowing a circulation of air for cooling the condensing chamber 2. These ventilating openings are shown somewhat more clearly at 45 in Fig. 4.

While in the foregoing description I have set forth the best form of my invention now known to me, I do not wish my claims to be limited to the details of the same, as it will be evident that many modifications may be made without departing from the spirit 105 of my invention. Thus as an example, instead of using two magnetizing coils 32 and 33, Fig. 4, I may use a single coil 46, Fig. 6, and, by connecting together the leads of the filament 47 and the anode 48, cause the 110 current from both to pass through the one coil. If desired, current may be conveyed to the filament and the anode through the same leading-in conductor, as shown in Fig. 7, in which current for the filament 49 and the anode 50 is supplied through the same 115 leading-in conductor.

What I claim as new and desire to secure by Letters Patent of the United States, is,

1. A combination of electrodes one at 125 least of which is of vaporizable material, a filament or conductor making contact with the vaporizable electrode and extending into close proximity to another of said electrodes, an armature secured to said filament, and a 130

- oil in circuit with said filament and operatively related to said armature.
2. The combination of an exhausted envelop, coöperating fixed electrodes therein one of which consists of vaporizable material, a filament initially engaging with said vaporizable electrode and capable of a motion of translation in said envelop out of engagement with said vaporizable electrode, an electrical connection between the filament and another electrode and a magnetizing coil acting to move said filament out of contact with the vaporizable electrode.
10. The combination of an exhausted envelop, a fluid electrode, a coöperating fixed electrode and a filament dipping in said electrode and movable bodily with respect to said envelop.
15. The combination of an exhausted envelop, a fluid electrode, a coöperating fixed electrode and a filament dipping in said electrode and movable bodily with respect to said envelop.
20. The combination of an exhausted envelop, coöperating fixed electrodes therein one of which consists of fluid material, a high resistance conductor engaging with said fluid electrode and disengageable from said fluid electrode by a movement of trans-
25. In a device of the character described, a conducting filament formed of carbon and having one end tipped with titanium carbid.
30. The combination of a sealed envelop, a vaporizable electrode, a non-vaporizable electrode, and a filament making contact with the vaporizable electrode and arranged to pass in proximity to but not in contact with the non-vaporizable electrode.
35. The combination of a sealed envelop, a filament therein, an armature carrying said filament, a solenoid in operative relation to said armature, an electrode separate from said filament and in circuit with said sole-
40. noid, a vaporizable electrode in contact-making-and-breaking relation to said filament.
45. The combination of a sealed envelop, a solid electrode supported therein, a relatively movable filament passing in proximity to said electrode, means for moving said filament, and a vaporizable electrode with which the filament is adapted to make and break contact.
50. The combination of a sealed envelop, a solid electrode supported therein, a relatively movable filament passing through a guide carried in fixed relation to said elec-
- trode, and electrical means for moving said filament.
10. The combination of a sealed envelop having a tubular portion surmounted by a bulb, and a reflector from which the bulbed envelop is supported.
15. The combination of a sealed envelop having a tubular portion surmounted by a bulb, and a ventilated reflector carrying the weight of said envelop.
20. The combination of an exhausted envelop, a vaporizable electrode, a coöperating electrode, a filament dipping in said vaporizable electrode, an electrical connection between the filament and the coöperating electrode, and means for moving said filament lengthwise of said envelop and out of contact with said vaporizable electrode.
25. The combination of an exhausted envelop, fixed main electrodes therefor, one at least of which consists of easily vaporizable material and a filament in contact with the vaporizable electrode and electrically connected to the coöperating electrode, said filament being capable of a movement of translation with respect to said envelop.
30. The combination of an exhausted envelop, fixed electrodes therefor, at least one of which consists of vaporizable material, a movable filament initially contacting at one end with a vaporizable electrode, an electrical connection for the other end of the filament, and means for giving to the filament a movement of translation in the envelop to break contact with the vaporizable electrode while maintaining electrical contact with the other end of the filament.
35. The combination of an exhausted envelop, fixed electrodes situated at opposite ends thereof, one of said electrodes consisting of easily vaporizable material and a filament in contact with said vaporizable material and movable bodily lengthwise of the envelop and out of engagement with said vaporizable material.
- In witness whereof, I have hereunto set my hand this 15th day of December, 1903.
